(57) **CLAIM**

We claim the ornamental design for a capotasto-shaped tuner, as shown and described.

DESCRIPTION

FIG. 1 is a left side perspective view of a capotasto-shaped tuner embodying our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The broken lines illustrate the portions of the design that form no part of the claim.
